VEHICLE SAFETY SIGNAL

Katie Adams, Box 271, Ketchum, Idaho 83340

Filed Mar. 31, 1972, Ser. No. 240,322

Term of patent 14 years

Int. Cl. D29—02

U.S. Cl. D72—1 H

FIG. 3

FIG. 1 is a perspective view of a vehicle safety signal showing my new design in the extended, operational position, the opposite side being identical.

FIG. 2 is an opposite side perspective view of the signal in a folded, stored position.

FIG. 3 is a bottom perspective view thereof. The stippling indicates reflective surfaces.

I claim:

The ornamental design for a vehicle safety signal, substantially as shown and described.
